CUTTING TABLE AND ATTACHMENT
THEREFOR

Benjamin Lang, New York, N. Y.

Application November 23, 1944, Serial No. 564,891

11 Claims. (Cl. 164—78)

This invention relates to tables for cutting cloth and is herein illustrated in some detail as embodied in a table having attachments for holding layers of folded cloth in such form that the attachments may be readily withdrawn after the folds of cloth have been suitably laid on the table thus leaving a smooth, uninterrupted surface on which the cloth lies ready for cutting.

Hitherto it has been the custom in many shops where cloth is to be cut, to drive in sharp-pointed nails in the table, and to lay the cloth in folds on the table face by stretching a length over one set of the projecting nail fronts, carrying the bight of the cloth back to an opposite set of nail points, impaling it on them, carrying the bight of the rest of the cloth back over the first set of nail points, and so on.

The driving of nails in different parts of the table damaged much of its surface, eventually destroying the surface of the table and was time-consuming.

Endeavors have been made to provide tables with cross bars to which pins were bolted, and the cross bars were held by screw clamps at opposite edges of the table, but these proved cumbersome and failed of adoption. It has also been proposed to mount impaling pins on a rotatable rod lying within a groove in the table top, so that rotation of the rod could carry the pins down into individual grooves extending at right angles to the rod groove, thus getting them out of the way, but this structure involved other difficulties in breaking up the smooth table top so that it interfered with satisfactory cloth cutting, and in getting the pins out of the cloth to turn them into the grooves.

In the form of the invention herein illustrated the foregoing and other difficulties and objections are overcome, and the cutting table is provided with an equipment of pins which firmly hold the cloth during cutting, is provided with pins which are readily removable and yet are quickly and accurately set as to firmly hold the cloth, and, moreover, the table top provides a smooth surface for the subsequent cutting operation.

In the form shown the device is provided with removable pins which may be clamped so as to project above the surface of the table for holding the cloth but which are readily removed after the cloth has been satisfactorily laid.

In the form shown the pins at one end of the cutting table are settable along an adjustable edge thus enabling the table to be readily and

efficiently used for laying cloth in folded lengths of any desired length.

Other features and advantages will herein-after appear.

5 In the accompanying drawings:

Fig. 1 is a plan view of the device with some parts broken away to show underlying structure;

Fig. 2 is a sectional side view on the line 2—2

10 of Fig. 1;

Fig. 3 is a sectional end view on the line 3—3 of Fig. 1;

Fig. 4 is a sectional side view on the line 4—4 of Fig. 1;

15 Fig. 5 is a side view of one form of pin;

Fig. 6 is a fragmentary side view showing how an alternative form of pin may be used; and

Fig. 7 is a sectional view along the line 7—7 of Fig. 6.

20 The table 10 is shown with a rectangular plank top 11 and legs 12 near the corners.

In the form shown, the table is adapted to firmly but releasably hold a set of vertical pins or spikes near one end 13, and to firmly but 25 releasably hold a second set of pins or spikes along an adjustable bar 14 which may be set near the opposite end 15 of the table 10.

In the form shown a bar 16 held to the end 13 of the table by screws 17 is notched at 18 to 30 receive the shanks 19 of a pin 20 so that the pin shank 19 is firmly clamped in the notch 18 and a facing notch 21 in a clamping bar 22 which extends along the full length of the bar 16, that is to say, the full width of the table 10.

35 In the form shown six pairs of pin notches 18 and 21 are adapted to hold six pins 20, and the pins are firmly held because the clamping bar 22 is adapted to slide over a small shelf 23 projecting from the bottom of the bar 16 and

40 to be drawn toward the bar 16 by turning bolts 24 which are threaded at 25 where they pass through the metal face 26 of the clamping bar 22, thus drawing the bar down by the enlarged bolt heads 27 which turn in pockets 28 behind the notched bar 16. The heads 27 may be lock nuts put on after the bolt is passed through the bar 16 and before the bar 16 is put in place.

45 Thus, when a pin or series of pins 20 are placed in the notches 18 and 21 with the clamping bar 22 released, the pin shank 19 rests on the shelf 23 and are, therefore, easily clamped in line.

The bolts 24 may be provided with thumb heads 29 to enable them to be readily tightened or released. The number of bolts may vary with the

width of the table 10, and the number of pins 20 and pin notches 18 and 21 will vary with the width of the table 10.

The clamping bar 22 is shown as extending beyond the metal bar 26 to provide a flat extension of the table to enable the turns in the folds of cloth to be evenly supported.

For holding the opposite ends of the folds of cloth there is shown a slideable cross bar 14, lying on the surface of the table 10 and provided with a depending lug 31 near its end 32 extends beyond the table edge at 30, so that the lug seats itself in any one of a number of spaced openings 33 in a side bar 34 held by screws 35 and holds its end of the cross bar 14 against sliding.

To give desired support to the opposite end 37 of the cross bar 14, and yet leave the edge 36 of the table clear so that it can be slid up against a second table for very wide cloth, the end 37 is shown provided with a seat 38 adapted to receive and hold against thrust the horizontal end peg 39 on a brace 40. The brace 40 is shown as lying diagonally on the face of the table 10 and carrying a depending peg 41 at its end 42, so that peg 41 may seat itself in an opening 33 and thus hold the brace 40 to hold the cross bar 14 firmly.

The cross bar 14 is shown as provided with vertical notches 43 which cooperate with notches 44 on a second clamping bar 45 to hold pins 20 which may be identical with the pins 20 set in the notches 18 and 21.

The pins 20 may be set up in the notches 43 and 44 when the clamping bar 45 has been released, and then rest upon the top of the table 10. They may be firmly clamped in place by screwing up bolts 46 having shanks 47 threaded where they pass through the clamping bar 45 and headed over at 48 at the front of the cross bar 14 so that screwing the bolts 46 draws the clamping bar 45 against the cross bar 14 to hold the pins 20 in the notches 43 and 44.

The heads 48 may be covered with small hoods 49 held by screws 50 to hold them in position when the clamping bars are opened.

To prevent accidental impaling of an operator's hands, or of goods, on the pins 20 in the notches 43 and 44, and to prevent catching the cloth when it is desired to roll the still-rolled cloth over the pins, the pins may be covered by a removable protecting bar 51 shown in the form of a bent-over flange on plate 52 which is hinged at 53 along the back upper edge 54 of the clamping bar 45. When the plate 52 is swung upwards and against the top of the pins 20 its flange 51 overlies the points 55 of the pins 20 to cover them, but is easily swung down and back out of the way to lie flat as an extension of the clamping bar 45.

The pins 20 shown in Figs. 2, 3 and 4 are easily pulled up out of the fabric after loosening the clamping bars 22 and 45 to release the pins 20 in the notches 43, 44. Then the clamping bar 45 and the cross bar 14 may be removed by sliding them out as a unit and the brace 40 may be removed by sliding it out, without danger of shifting the cloth.

The pins 20 in the notches 18 and 21 are usually removed before cutting the cloth. They are removed by releasing the clamping bar 22 to release the pins.

Sometimes it is preferable to use the alternative form of pin 56, shown in Fig. 5, which has the same shape of shank 19, but is provided with an enlarged spear-shaped head 57 which tends to

retain the cloth impaled upon it, but allows the pin 56 to be readily withdrawn through the cloth impaled upon it.

When the cross bar 14 with its clamping bar 45 and brace 40 is withdrawn from beneath the folded cloth, and the pins 20 have been withdrawn from their notches 18 and 21, and the clamping bar has been re-clamped against the end bar 16, the table presents an almost perfectly smooth surface on which the cloth may lie, and against which it may be pressed by the usual weighted-down cutting pattern, not shown. Thus the cloth is uniformly held to be cut by the usual power cutter, or by a hand cutter, as the case may be.

Figure 6, shows how a special form of pin 57 may be used to overcome some of the difficulties which arise in laying many layers of cloth on a cutting table. That difficulty arises from the fact that each layer of cloth impaled upon a row of pins puts increased tension upon the rows of pins tending to bend the pins toward the center of the table thus altering tensions as the pins bend.

In order to overcome that difficulty there may be provided the special pins 56' having round shanks 58 adapted to fit in a series of half-round matched notches 59 in the cross bar 14 and second clamping bar and in the table end 13 and its clamping bar 22.

The pins 56' are adapted to be set up after a number of folds of cloth 64 have been impaled on set up pins 20. To enable the pins 56' to be thus set up without lifting the folded cloth from the pins 20, each pin 57 includes an off-set portion 60 above the horizontal reach 61.

In the form shown the horizontal reach 61 lies close against the top of the clamping bar 45. Each pin 56' also includes a top impaling length 62 beginning about the height of the top of points 55 of the pins 20, and high enough to hold the desired further folds of cloth like the folds 64.

The length 62 is connected by an upper reach 63 with the offset portion 60, with the result that the pins 56' can be inserted in their notches 59 by partly lifting the folds 64, placing the shanks 58 in the notches 59, dropping the cloth folds into the opening found by offset 60, and then laying more layers of cloth and impaling them on the pins 57 at each end of the table.

While the half round recesses fitting loosely about the lower ends of the pins 56' cooperate with the cloth to hold the pins in position, a strip of metal 67 may be inserted between the ends of the layers of cloth and the offset portion 60 as shown in Figs. 6 and 7 to cooperate also in holding the pins in position. The strip of metal 67 may have vertical grooves 68 adapted to register with the offset portion 60 of the pins 56'.

While rounded recesses 59 are shown in Fig. 1 for holding the lower ends of the pins, they may be omitted and the ends of the pins inserted loosely in the spaces between the clamping bar intermediate the regular pins 56.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described in some detail one embodiment of the invention, what is claimed is:

1. In a cutting table the combination with an end having a bottom shelf adapted to form a rest for pins resting in notches in the end of a notched clamping bar forming an extension of

the table top and slidable along the shelf, and means for drawing the clamping bar toward the end to clamp the pins in the notches.

2. In a cutting table the combination with an end having a bottom shelf adapted to form a rest for smooth-shanked pins resting in notches in the end, of a notched clamping bar forming an extension of the table top and slidable along the shelf, a metal bar forming the face of said end, and bolts threaded in the clamping bar and headed behind said metal bar to cause the bolts to draw the clamping bar toward the end so that the pins are clamped between notches in the bar and the notches in the end.

3. In a cutting table, the combination with removable end pins, of a side support attached to one side of the table so that a second row of pins may be wholly supported from that side leaving the other side clear, said support including spaced openings adapted to be engaged by both a cross-bar carrying said second row of pins, and by a brace holding said cross-bar in position.

4. In a cutting table, the combination with removable end pins, of a side support attached to one side of the table and including spaced openings adapted to receive a lug of a pin-holding cross bar, said openings also adapted to receive a lug on a cross-bar brace, so that pins on the cross-bar may be firmly held where clamped against said cross-bar by a clamping bar.

5. In a cutting table, a side support along one edge, a notched cross-bar adjustably supported by said support, a notched clamping bar adapted to hold pins in the cross-bar notches, and means for drawing the clamping bar to the cross-bar to hold the pins.

6. In a cutting table, a side support along one edge, a notched cross-bar adjustably supported by said support, a notched clamping bar adapted to hold pins in the cross-bar notches, a shield for the points of the pins hinged to the clamping bar and adapted to be swung over the pin points or out of the way, and means for drawing the clamping bar to the cross bar to hold the pins.

7. In a cutting table, a side support along one edge, a notched cross-bar adjustably supported by said support, a notched clamping bar adapted to hold pins in the cross-bar notches, a shield for the points of the pins hinged to the clamping bar and adapted to be swung over the pin points or out of the way, and bolts threaded in the clamping bar and having heads outside the cross bar to draw the clamping bar to clamp the pins.

10 8. A cutting table attachment including a cross-bar to lie upon the table, an end lug to hold it in position by seating itself in an opening at the table edge, a clamping bar adapted to be drawn against the cross bar to clamp pins between them, and a shield hinged to the clamping bar and adapted to be swung from open position to cover the points.

9. A cutting table attachment including a notched cross-bar to lie upon the table, an end lug to hold it in position by sealing itself in an opening at the table edge, a notched clamping bar adapted to lie against the cross-bar to clamp pins in the notches, means for drawing the clamping bar against the cross-bar, and a hinged shield carried by one of said bars having a lug adapted to overlie points of the clamped pins and to be swung away from the pins.

20 10. A cutting table attachment including a cross bar adapted to lie upon the table, and end lug adapted to hold it in position, a side bar including a series of openings to receive said lug to adjust the cross-bar, and a back for the cross bar including a lug to lie in another of said openings.

30 11. A pin adapted to be set on a cutting table, including a shank, a horizontal reach extending from said shank, an offset rising from the end of said reach, a second reach at the other end of the offset, and an impaling stretch rising from the second reach.

BENJAMIN LANG.
